UNITED STATES PATENT OFFICE.

JAMES A. HAWLEY, OF CANANDAIGUA, NEW YORK.

VAGINAL SYRINGE.

SPECIFICATION forming part of Letters Patent No. 295,755, dated March 25, 1884.

Application filed November 15, 1881. (Model.)

To all whom it may concern:

Be it known that I, JAMES A. HAWLEY, a citizen of the United States, residing at Canandaigua, in the county of Ontario and State 5 of New York, have invented certain new and useful Improvements in Vaginal Syringes; and I do hereby declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 This invention has for its object to furnish a vaginal syringe whereby water may be injected, and instantly and forcibly removed or ejected as rapidly as injected, and whereby, when desired, a current of water may be ob-

20 tained by the injection from one reservoir and the forcible and instantaneous removal or education to another reservoir, and thereby preventing the possibility of injecting the womb, by the accumulation and pressure of the water, 25 and preventing the undue and painful expansion of the walls of the vagina by the same causes.

It consists in the combination, with an ordinary speculum, of two tubes held in a plug 30 snugly fitted to the speculum, and provided with suction-bulbs on both tubes, whereby the water may be injected by the one bulb and taken up by the other as rapidly as injected, and so that, if desired, the water may be thrown 35 back from one bulb to the other, thereby creating a current.

In the drawings, Figure 1 is a side elevation of an ordinary speculum having my improvements applied thereto, and Fig. 3 is a vertical 40 section of the same. Fig. 2 is a vertical section, showing the tubes supported by a sleeve or cylindrical plug inserted at the outer end of the speculum; and Fig. 4 is a detail view.

a is the well-known speculum in common 45 use.

b is head-piece or plug, made preferably of elastic rubber, and snugly fitted into the speculum. It is so fitted that it can be removed when desired.

50 *b' b'* are two pipes, preferably hard rubber,

put through openings in the head-piece, and having their inner ends arranged flush with the inner face of said head-piece. The outer ends of these pipes are projected, as shown clearly in Fig. 2, and are slightly enlarged, so 55 as to provide means for holding the ends of the flexible tubes or compressible bulbs. In Fig. 2 the pipes are shown extended beyond the outer end of the speculum and supported by a disk or plug, *b'*, of any suitable material. 60

c c are the flexible tubes, which are attached to the outer ends of the pipes *b' b'*. To the tubes *c c* are connected the bulbs *d d*.

The device, as shown in full lines, Figs. 1 and 3, is intended to be used in throwing water back and forth between the bulbs, and is 65 specially useful in many diseases of the vagina and womb.

In dotted lines, Figs. 1 and 2, is shown the application of two ordinary syringes to my 70 device. The bulbs and flexible tubes shown in full lines, Figs. 1 and 3, can be readily slipped off the pipes *b'*, and the ends of the tubes of the syringes shown in dotted lines be placed thereon, and by this arrangement a continuous flow 75 of water can be given. The water will be taken up by the exit-bulb and discharged into a vessel prepared to receive it.

By the use of this syringe the cleansing of the vagina can be effected while the patient 80 remains in bed, and there will result no soiling or wetting of the bed-clothing.

I employ, as will be seen, an injection-bulb and a take-up bulb, whereby perfect cleanliness is preserved.

The body or speculum *a* is adapted to fit 85 snugly in the vagina and prevent water from dribbling outward along its outer side.

Having thus described my invention, what I claim, and desire to secure by Letters Patent, 90 is—

1. The improved vaginal syringe hereinbefore described, wherein an ordinary speculum or vaginal tube is fitted with a plug inclosing two pipes of suitable lengths, in combination 95 with compressible and expandable induction and education bulbs, whereby water may be injected and forcibly withdrawn as rapidly as injected, substantially as set forth.

2. The combination, with a speculum or vag-

inal tube, of the plug b , fitted to the inner end of the speculum, the inflexible pipes $b' b'$, having their inner ends inclosed by and flush with the inner face of plug b , and having their opposite ends projected out of the opposite end of the speculum, a supporting-plug, b^2 , fitted to the outer end of the speculum and around the pipes $b' b'$, and induction and eduction bulbs, whereby water may be injected and for-

cibly withdrawn as rapidly as injected, substantially as described.

In testimony whereof I affix my signature, in presence of two witnesses, on this 14th day of November, 1881.

JAMES A. HAWLEY.
